UNITED STATES PATENT OFFICE.

CHARLES ISID HOOVER AND WALTER FRANKLIN BENTON, OF FORD CITY, PENNSYLVANIA.

RUNNER FOR GRINDING PLATE-GLASS.

1,178,236.

Specification of Letters Patent.

Patented Apr. 4, 1916.

Application filed September 21, 1915. Serial No. 51,830.

To all whom it may concern:

Be it known that we, CHARLES I. HOOVER, and WALTER F. BENTON, residing at Ford City, in the county of Armstrong and State 5 of Pennsylvania, have invented certain new and useful Improvements in Runners for Grinding Plate-Glass, of which the following is a specification.

Our invention, which generally relates to 10 machines or apparatus for grinding plate glass, more particularly has reference to an improved means for securing the grinding runner to the grinding deck head or disk.

As is well known to those familiar with 15 the use of plate glass grinding machines, of that type in which the glass plate or sheet is held on the surface of a rotary table and ground upon its upper surface by grinding decks or runners, in the use of the ordinary 20 types of grinding decks, the heads of the screws that secure the runners frequently break off and the runners break at the screw holes. Further, in the common types of grinding decks, the connections that join 25 the runners to the deck head or disk soon wear loose and thereby afford room for grit to accumulate, to such an extent that a proper grinding of the glass plate is impaired. Again, in other forms of glass 30 grinding decks, the runners are usually attached to a deck mounted on the under face of the deck or runner carrier by wood screws and in the use of such forms of grinding decks, it is necessary to plug the 35 screw holes in the wooden deck every time the runner blocks are changed requiring much expense and labor in putting the deck head in shape for the attachment of the new runner blocks.

40 Our invention primarily has for its object to provide an improved construction of grinding deck or head in which an improved means for attaching the blocks directly to the metal deck head or carrier in such 45 manner that the use of a wooden deck and wooden screws is dispensed with and by which the runner blocks can be quickly, and at a minimum expense of labor, secured to the deck, and in such manner that the connection is such that the runners can be easily 50 adjusted and held up solid against the deck and all danger of grit accumulations thereby practically overcome.

With further objects in view that will

hereinafter appear, our invention consists 5 in the peculiar combination and novel arrangement of the parts hereinafter explained, specifically pointed out in the appended claims and illustrated in the drawing, in which—

Figure 1 is a plan view of a portion of the under or face side of a grinding runner, so much of the runner portion being shown necessary to illustrate a practical embodiment of our invention. Fig. 2 is a vertical 60 section thereof taken substantially on the line 2—2 on Fig. 1. Fig. 3 is a detail vertical section of the cast iron bottom plate or deck portion of the grinding deck, some of the runner bars and the means for fastening the runner bars to the said deck plate or disk. Fig. 4 is a plan view of the bottom side of the parts shown in Fig. 3. Fig. 5 is a plan view of one of the runner bars.

In carrying out our invention, we provide 65 runner bars 2 to which the blocks 1 are integrally or otherwise made fast, and said bars vary in length to receive from one block 70 to fifteen or more blocks.

In assembling the parts, the runner sections 75 are alined to extend entirely across the deck head of the grinder disk 5, the latter being preferably a hollow casting having a central hub 6 to provide for securing it to any kind of shaft 7, whose lower end does 80 not extend clear through the deck head.

Each runner bar 2 has its opposite edges 85 beveled, and the bevels 8, which extend the full length of the said bars 2, form hangers for being engaged by the opposite beveled 90 edges of clamping bars 9—90.

Each clamp bar 9 engages the adjacent beveled edges of a pair of runners, as is clearly shown in Figs. 4 and 5, by reference to which it will be seen the said bars 9—90 95 at suitable intervals have countersunk screw holes 10 to receive the machine screws 11 that engage screw apertures 12 in the bottom or deck head of the casting 5, and it will be also seen that the alternate ones are 100 screwed up tight against the deck head while the other alternate ones 90 of the said bars have their bevels so shaped that when screwed home they are held spaced apart from the deck head, in practice, about one-eighth of an inch.

By applying the alternate sets of clamping bars in the manner stated, when it is de-

sired to remove the runner bars, it is only necessary to loosen the alternate clamping bars 90 by withdrawing their clamp screws enough to permit the runner bar to pass in or out when reblocking, it being understood that the fixedly held clamping bars 9 tend to keep the runner bars as they pass in or out in engagement with the said bars 9.

Each runner bar 2 has a countersunk 10 screw hole 21 to receive a screw 22 for holding the bar secure on the deck head and against working endwise out from the clamping bars.

By reason of forming the grinder blocks 15 or runners having beveled or flanging flanges 11, and providing beveled edged clamp bars that co-operate with the said runners and are removably attached to the deck or head of the casting 5 in the manner shown 20 and described, the runners can be quickly applied or removed and since the machine screws engage the screw taps 12 that extend entirely through the deck portion of the casting 5, the parts can be quickly and effectively tightened up in case they tend to loosen up, and the cost of labor for making wooden pins for plugging up the screw holes, incident in the use of wooden decks, and time in fixing up the said holes, is saved; 25 the connections shown and hereinbefore described also operate to prevent grit from working into any place on the face of the runner blocks or the deck, and guard the runner bar against breaking at the screw holes, thereby avoiding the danger of breaking the glass which often occurs when wood screws are used for fastening the runner blocks onto a wooden deck.

While we have shown the runner bars in 30 parallelism, they can be opposite one another or in a staggered relation so as to keep

the sand or grit from passing through too freely.

What we claim is:

1. A grinding runner, comprising a rigid 45 frame having a deck, a series of runner bars engaging the deck and a set of clamping bars for engaging the runner bars, and means for securing the clamping bars to the deck. 50

2. A grinding runner, comprising a rigid frame having a deck, a series of runner bars engaging the deck and a set of clamping bars for engaging the running bars, means for securing the clamping bars to the deck, 55 the said runner bars and the said clamping bars having engaging beveled edges.

3. A grinding runner comprising a rigid frame having an integral deck, a series of runner bars engaging the deck spaced apart 60 at predetermined distances and clamping bars that extend entirely across the deck, one of the said bars being located between each pair of runner bars, and engaging the adjacent edges of each of said pairs of runner bars, and means for securing the clamping bars to the deck. 65

4. A grinding runner comprising a rigid frame having an integral deck, a series of runner bars engaging the deck spaced apart 70 at predetermined distances, clamping bars that extend entirely across the deck, one of the said bars being located between each pair of runner bars, said clamping bars and the runner bars having co-engaging beveled 75 edges, the deck having screw tapped apertures, the clamping bars having screw holes and machine screws that engage the said holes and the said screw taps.

CHARLES ISID HOOVER.
WALTER FRANKLIN BENTON.
